UNITED STATES PATENT OFFICE.

JACOB K. ALTEMUS, OF PHILADELPHIA, PENNSYLVANIA.

YARN-WINDING MACHINE.

Application filed January 17, 1923. Serial No. 613,080.

To all whom it may concern:

Be it known that I, JACOB K. ALTEMUS, a citizen of the United States, residing at Philadelphia, in the county of Philadelphia and State of Pennsylvania, have invented certain new and useful Improvements in Yarn-Winding Machines, of which the following is a specification.

This invention relates to improvements 10 in machines for winding yarn upon bobbins wherein are employed a yarn guide for delivering the yarn to the bobbin, means for raising and lowering the yarn guide for placing successive layers of yarn upon the bobbin, means for imparting gain movements to the yarn guide during the operations of raising and lowering the same to build the layers of yarn upon the bobbin, and means to arrest the gain movements of 15 the yarn guide immediately upon the breakage or discontinuance of the yarn being delivered to the bobbin.

The objects of my invention are: first, to provide a novel, sensitive and efficient 20 means which may be controlled automatically by very fine counts of yarn to arrest the gain movements of the yarn guide upon the breakage or discontinuance of the yarn being guided thereby to the bobbin; and, second, to provide novel and efficient means 25 for imparting the gain movements to the yarn guide which will have a wide range of adjustment for variations in the gain movements of the yarn guide and which 30 will be capable of adjustment for minute variations in different gain movements for yarns of different sizes or counts, and which 35 may be quickly changed or adjusted to meet the requirements of a change of yarn.

With the foregoing and related objects 40 in view, the invention consists in the novel construction, combination and arrangement of parts hereinafter described and claimed.

In the accompanying drawings, illustrating 45 my invention,

Figure 1 is an end view of a yarn winding machine embodying my invention, part of the main frame of the machine being broken away.

Figure 2 is a front view thereof.

Figure 3 is a sectional detail of the winding mechanism, partly broken away, on line 3—3 of Fig. 2.

Figure 4 is a top view of the bobbin spin-

dle, bobbin, yarn guide and adjuncts, showing the mechanism for imparting the gain movements to the guide and for automatically stopping such movements.

Figure 5 is a sectional detail, in elevation of part of the mechanism shown in Fig. 4.

Referring to the drawings, the main frame of the machine includes end standards 2 and a horizontal bar 4 connecting them.

A bobbin receiving and rotating spindle 5 is mounted to rotate in bearing 6 formed on a bracket 7 which is secured to and projects from the frame bar 4. The lower end portion of the spindle 5 is provided with a whirl disc 8 which rests normally on the leather covering 9 secured on the periphery of a driving wheel 10. The driving wheel 10 is carried by a horizontal shaft 11 which extends between and is journaled in bearings on the standard 2. The shaft 11 constitutes the main driving shaft of the machine and one end portion thereof extends outwardly from one of the standards 2 and it is provided with fast and loose pulleys 12 and 13, respectively, for the application thereto of a driving belt for actuating the machine.

The machine is provided with a vertically reciprocable builder frame or support 14 comprising a horizontal rail 15 and vertically arranged, parallel shafts or rods 16 connected to and extending downwardly from the respective end portions of the rail 15. The shafts 16 are vertically slidable in bearings 17 on the end standards 2, and their lower end portions are provided with brackets 18 carrying rollers 19 which rest upon cams 20 on a horizontal shaft 21. The shaft 21 extends between and is journaled in bearings on the end standards 2 and it is driven by a gear wheel 22 thereon in mesh with a pinion 23 on the main driving shaft 11. The cams 20 are shaped to effect the desired up and down movements of the builder frame or support 14 during the operation of the machine.

The general construction and operation of the parts thus far described are common and well known in this art, and no detailed description or illustration thereof is deemed necessary herein.

The rail or support 15 carries a builder

screw 24 which rises fixedly from a plate 25 screwed thereon. Rotatably mounted on the screw 24 is a nut gear 26 having a downwardly extending sleeve 27 surrounding the screw 24 and having a plate or arm 28 engaged with the thread of the screw 24 to cause upward movement of the nut gear 26 when it is turned in the direction of the arrow in Fig. 4. One end of the plate 28 is pivoted, at 29, to the gear 26, and the other end of the plate 28 is held normally in engagement with the screw 24 by a spring 30 connecting the plate 28 and gear 26. After moving the arm 28 from engagement with the screw 24 the nut gear 26 may be raised or lowered on the screw into any desired position thereon.

The nut gear 26 carries an arm 31 having a sleeve 32 which surrounds and is adapted to turn on the gear sleeve 27. The arm 31 is provided with a stud screw 33 on which is rotatably mounted a gear wheel 34 which is constantly in mesh with the nut gear 26 and which is adapted to be moved into and out of mesh with a pinion 35 when the arm 31 is turned on the gear sleeve 27 for purposes presently appearing.

Fulcrumed on the arm 31 is a thread guiding lever 36 comprising a collar 37 and two arms 38 and 39 projecting therefrom. The collar 37 surrounds the screw 24 and the upper end portion of the sleeve 32 of the arm 31; and the free end of the arm 38 carries a head 40 having a thread receiving and guiding slot 41, as clearly shown in Figs. 4 and 5. The lever arm 39 extends into a slot in the upwardly extending flange on one end of a lever 42 which is pivoted, at 43, on the arm 31. The other end of the lever 42 is fulcrumed against a post 44 which rises fixedly from the plate 25 on the builder rail 15 and between which and the pinion 35 the lever 42 extends.

The post 44 extends parallel to the screw 24 and through an opening 45 in the arm 31 and permits the arm 31 and lever 42 to be raised and lowered with the nut gear 26 without otherwise changing their relation to the post 44.

The levers 36 and 42 and arm 31 are related to each other and to the post 44 and pinion 35 so that, when the head 40 is drawn toward the bobbin 46 on the spindle 5 by a strand of yarn 47 being fed to the bobbin, the tension of the yarn 47, even though it be extremely light will maintain the levers 36 and 42, arm 31 and gear wheel 34 in the positions shown by full lines in Fig. 4, with the gear wheel 34 in mesh with the pinion 35, causing the nut gear 26 to be turned by the gear 34 when it is turned by the pinion 35. Should the yarn 47 break or should its delivery to the head 40 be discontinued, stopping the pull of the yarn 47 on the head 40 toward the bobbin 46, the

pinion 35 will be thereby permitted to move the levers 36 and 42, arm 31 and gear wheel 34 to the positions shown by dot-and-dash lines in Fig. 4, and thereby stop the actuation of the nut gear 26 by the pinion 35 all for purposes hereinafter explained.

The pinion 35 is formed on the upper portion of a vertical shaft 48 which is arranged parallel to the builder screw 24 and post 44; and the pinion 35 is elongated and it extends the full distance of vertical travel of the gear wheel 34 with the nut gear 26 so that the gear wheel 34 may be moved into and out of mesh with the pinion 35 in any position of the nut gear 26.

The vertical shaft 48 is fitted to turn in suitable bearings on a bracket 50 on the frame bar 4, and the lower end of the shaft 48 is provided with a bevel gear wheel 51 adapted to mesh with a similar wheel 52 on a horizontal shaft 53 which extends parallel to the main driving shaft 11 and which turns in suitable bearings on the main frame of the machine.

The shaft 53 is provided with a ratchet wheel 54 adapted to be turned by two pawls 55 and 56 arranged rearwardly and forwardly thereof, respectively. The rearward pawl 55 is pivoted, at 57, to the lower end portion of an arm 58 which extends downwardly from a bracket 59 which is secured upon the builder rail or support 15. The arm 58 is secured to the bracket 59 by a set screw 60 which extends through a slot 61 in the arm 58 and permits the arm 58 and pawl 55 to be adjusted vertically relatively to the builder frame 14 and ratchet wheel 54. The forward pawl 56 is pivoted, at 62, on a collar or bracket 63 which is secured to one of the rods 16 of the builder frame 14 by screws 64 in a manner to be vertically adjustable thereon.

The pawl 55 is moved upwardly toward the ratchet wheel 54 by a counter weight 65 formed thereon; and the pawl 56 is moved downwardly toward the ratchet wheel 54 by gravity. The forward pawl 55 is adapted to engage and move the ratchet wheel 54 during each downward stroke of the builder frame 14, and the forward pawl 56 is adapted to engage and move the ratchet wheel 54 during each upward stroke of the builder frame 14.

The extent to which the pawl 55 moves the ratchet wheel 54, during each downward stroke of the builder frame 14, is governed by a stop screw 66 which is vertically adjustable in a lug 67 on the pawl carrying arm 58. During the downward movement of the builder frame 14 the lower end of the screw 66 engages the pawl 55 and moves it from operative engagement with the ratchet wheel 54 after the pawl has moved the ratchet wheel a predetermined distance gov-

erned by the position of adjustment of the screw 66. It will thus be understood that the screw 66 may be adjusted to cause the pawl 55 to turn the ratchet wheel 54 a very slight distance at each down stroke of the builder frame 14, or a more extended distance, as desired. A suitable set nut 68 is provided on the screw 66 to engage the lug 67 to lock the screw 66 in different positions 10 of adjustment.

The extent to which the pawl 56 moves the ratchet wheel 54, during each upward stroke of the builder frame 14, is governed by a vertically adjustable stop rod 69, the lower 15 end portion of which extends through a lug 70 on the collar 63 to a position directly above an arm 71 on the pawl 56, and the upper end portion of which is screw-threaded and screwed into and through the bracket 20 59 on the rail 15. The upper end of the rod 69 is provided with a suitable head 72 by means of which it may be turned for vertical adjustment; and the threaded portion thereof is provided with a set nut 73 to engage 25 the bracket 59 and lock the rod 69 in different positions of adjustment. During the upward movement of the builder frame 14, the lower end of the rod 69 engages the arm 71 of the pawl 56 and moves the pawl 30 from operative engagement with the ratchet wheel 54 after the pawl has moved the ratchet wheel a predetermined distance governed by the position of adjustment of the rod 69. It will thus be understood that the 35 rod 69 may be adjusted to cause the pawl 56 to turn the ratchet wheel 54 a very slight distance at each upward stroke of the builder frame, or a more extended distance, as desired.

40 In Fig. 3 the pawls 55 and 56 are shown by full lines in the positions they occupy at the lower end of the builder frame stroke, and by dot-and-dash lines in the positions they occupy at the upper end of the builder frame stroke, the screw 66 and rod 69 being adjusted to permit the pawls to turn the ratchet wheel 54 to the maximum extent during each up and down stroke of the builder frame. By adjusting the screw 66 45 and rod 69 downwardly the extent of the movement of the ratchet wheel 54 by the pawls may be decreased to any desired extent.

The bracket 6 has a hand lever 74 fulcrumed, at 75, thereon and provided with arms 76 and 77 which extend therefrom to positions beneath collars 78 and 79 carried by the whirl 8 and shaft 48, respectively. The arms 76 and 77 are provided with beveled portions 80 and 81 to engage the collars 78 and 79 and raise the whirl 8 and gear wheel 51 from operative engagement with the wheels 10 and 52, respectively, when the hand lever 74 is moved for that purpose. 60 The whirl 8 is slidably fitted to a square

portion of the spindle 5, and the shaft 48 is 65 slideable in its bearings to permit them to be moved by the lever 74.

The operation of the machine, briefly described, is as follows:

70 Power is applied to the main driving shaft 11 and the rotation thereof causes the wheel 10 to rotate the whirl 8 and spindle 5, and the cams 20 to raise the builder frame 15 and permit it to descend by gravity.

75 During this operation, the yarn 47 is fed to the bobbin 46 upon the spindle 5 and wound thereon guided by the head 40 on the yarn guiding lever 36; and, at each up and down stroke of the builder frame 14, the 80 yarn guiding lever 36 is raised and lowered to cause the yarn to be wound in spiral-like superposed layers upon the bobbin 46.

85 As the yarn layers are thus wound upon the bobbin 46, the nut gear 26 is periodically moved upwardly on the screw 24 relatively to the builder frame 14 to impart the upward gain movements to the yarn guiding lever 36 relatively to its constant up and down movements by the builder frame 14, to build 90 the successive layers of yarn upwardly upon each other and upon the bobbin 46.

95 The gain movements of the yarn guiding lever 36 are effected by the operation of one or both pawls 55 and 56 on the ratchet wheel 54 and by the gearing between the ratchet wheel 54 and the nut gear 26 causing the latter to be turned upon the screw 24, screw 66 and rod 69 to cause either or both pawls 55 and 56 to be actively engaged 100 with the ratchet wheel 54 for the full length or fraction of the stroke of the builder frame 14. When the action of one pawl will suffice for the gain movement, the rearward pawl 55 may be moved downwardly on its pivot until its counter weight 65 passes over the vertical centre of the pivot and rests against a projection on the arm 58 and holds the pawl 55 in an inoperative position.

110 When the forward pawl is set to effect the gain movement along for a low count of yarn and the rearward pawl 55 has been set to operate in conjunction with the rearward pawl in the same setting thereof to effect the gain movement for a higher count or coarser yarn, the change from one count to the other may be quickly effected by swinging the pawl 55 into and out of operative 115 relation to the ratchet wheel 54, and without changing the adjustments of the screw 66 and rod 69.

120 The yarn 47 passing through the head 40 to the bobbin 46 maintains the levers 36 and 42, arm 31 and gear wheel 34 in the full line position shown in Fig. 4, during the winding operation; and should the yarn 47 break or run out, the pinion 35 will immediately move the parts to the dot-and-dash line 125 position shown in Fig. 4, and thereby break 130

the gearing between the ratchet wheel 54 and nut gear 26 by moving the gear wheel 34 out of mesh with the pinion 35 and thus discontinue the gain movements imparted 5 to the yarn guiding lever 36 without stopping its up and down movements by the builder frame 14, so that after the broken yarn has been repaired or a fresh strand of 10 yarn has been run through the head 40 to the bobbin 46, the repaired or fresh strand will draw the yarn guiding arm 36 back to the full line position and thereby cause it to resume its gain movements at the same 15 position with respect to the yarn layers on the bobbin 46 where the gain movements were discontinued.

When it is desired for any reason to stop the rotation of the bobbin 46 and the gain movements of the yarn guiding lever 36, the 20 same may be done by operating the hand lever 74 to raise the whirl 8 and the gear wheel 51 from engagement with the wheels 10 and 52, respectively.

It will be understood that any desired 25 number of spindles 5 with their yarn guiding arms 36 may be employed on the machine all operated and controlled in common by the builder frame 14 and shafts 11, 21 and 53.

30 I claim as my invention:

1. In a yarn winding machine, the combination of a support, a bobbin spindle, rotating means for the spindle, a pinion, means to impart intermittent movements of 35 partial rotation to the pinion, a non-rotating builder screw, a nut gear operatively engaged with the screw, an arm pivoted on a part of the nut gear and movable toward and from the pinion, a gear wheel carried 40 by the arm in mesh with the nut gear and movable by and with the arm into and out of mesh with the pinion, a thread guiding lever fulcrumed on the arm, and an auxiliary lever pivoted on the arm and having 45 one arm engaging the thread guiding lever and another arm fulcrumed on a part of said support, whereby when an arm of the thread guiding lever is moved toward the spindle the auxiliary lever will be operated 50 to move the said gear wheel into mesh with the pinion.

2. In a yarn winding machine, the combination of a support, a bobbin spindle, rotating means for the spindle, a pinion, means to impart intermittent movements of 55 partial rotation to the pinion, a non-rotating builder screw, a nut gear operatively engaged with the screw, an arm pivoted on a part of the nut gear to turn on the axis 60 thereof, a gear wheel carried by the arm in mesh with the nut gear and movable by and with the arm into and out of mesh with the pinion, a thread guiding lever fulcrumed on the arm on the axis of the nut gear, and an 65 auxiliary lever pivoted on the arm and hav-

ing one arm engaging the thread guiding lever and another arm fulcrumed on a part of said support, whereby when an arm of the thread guiding lever is moved toward the spindle the auxiliary lever will be 70 operated to move the said gear wheel into mesh with the pinion.

3. In a yarn winding machine, the combination of a support having a post rising fixedly therefrom, a builder screw rising 75 fixedly from the support in parallel relation to the screw, a bobbin spindle, rotating means for the spindle, a pinion, means to impart intermittent movements of partial rotation to the pinion, a nut gear operatively engaged with the builder screw, an arm pivoted on a part of the nut gear and movable toward and from the pinion, a gear wheel carried by the arm in mesh with the nut gear and movable by and with the arm 80 into and out of mesh with the pinion, a thread guiding lever fulcrumed on the arm, and an auxiliary lever pivoted on the arm and having one arm engaging the thread guiding lever and another arm fulcrumed on said post, whereby when an arm of the thread guiding lever is moved toward the spindle the auxiliary lever will be operated 85 to move the said gear wheel into mesh with the pinion.

4. In a yarn winding machine, the combination of a frame, a vertically movable support guided by the frame, means to reciprocate the support, a post rising fixedly from the support, a builder screw rising 100 fixedly from the support in parallel relation to the screw, a bobbin spindle, rotating means for the spindle, a pinion, means to impart intermittent movements of partial rotation to the pinion, a nut gear operatively engaged with the builder screw, an arm pivoted on a part of the nut gear and movable toward and from the pinion, a gear wheel carried by the arm in mesh with the nut gear and movable by and with the arm 105 into and out of mesh with the pinion, a thread guiding lever fulcrumed on the arm, and an auxiliary lever pivoted on the arm and having one arm engaging the thread guiding lever and another arm fulcrumed on said part, whereby when an arm of the thread guiding lever is moved toward the spindle the auxiliary lever will be operated 110 to move the said gear wheel into mesh with the pinion.

5. In a yarn winding machine, the combination of a frame, a bobbin spindle, means to rotate the spindle, a vertically movable support guided by the frame, means to reciprocate the support, a non-rotating builder screw, carried by the support, a nut gear operatively engaged with the screw, a yarn guide carried by the nut gear, a ratchet wheel, gearing between the ratchet wheel and the nut gear, and two pawls carried by the sup- 120 125 130

port, one pawl actuating the ratchet wheel on the down stroke of the support and the other pawl actuating the ratchet wheel on the up stroke of the support.

5 6. In a yarn winding machine, the combination of a frame, a bobbin spindle, means to rotate the spindle, a vertically movable support guided by the frame, means to reciprocate the support, a non-rotating builder

10 screw carried by the support, a nut gear operatively engaged with the screw, a yarn guide carried by the nut gear, a ratchet wheel, gearing between the ratchet wheel and the nut gear, two pawls carried by the

15 support, one pawl actuating the ratchet wheel on the down stroke of the support and the other pawl actuating the ratchet wheel on the up stroke of the support, and adjustable means for varying the extent of move-

20 ment of the ratchet wheel by one of said pawls.

7. In a yarn winding machine, the combination of a frame, a bobbin spindle, means to rotate the spindle, a vertically movable sup-

25 port guided by the frame, means to reciprocate the support, a non-rotating builder screw carried by the support, a nut gear operatively engaged with the screw, a yarn guide car-

30 ried by the nut gear, a ratchet wheel, gear- ing between the ratchet wheel and the nut gear, a pawl pivotally connected to the sup-

35 port for actuating the ratchet wheel during the movement of the support in one direc-

40 tion, and adjustable means for varying the extent of movement of the ratchet wheel by

45 the pawl at each stroke of the support in the said direction.

8. In a yarn winding machine, the combination of a frame, a bobbin spindle, means

40 to rotate the spindle, a vertically movable support guided by the frame, means to reciprocate the support, a non-rotating builder screw carried by the support, a nut gear oper-

45 atively engaged with the screw, a yarn guide carried by the nut gear, a ratchet wheel,

and the nut gear, a pawl pivotally connected to the support for actuating the ratchet wheel during the movement of the support in one direction, and a stop part carried by the support and adapted to be engaged by the pawl to cause the disengagement of the pawl from the ratchet wheel during the movement of the support in the said direc-

50

55

9. In a yarn winding machine, the combination of a frame, a bobbin spindle, means to rotate the spindle, a vertically movable support guided by the frame, means to reciprocate the support, a non-rotating builder

60

screw carried by the support, a nut gear operatively engaged with the screw, a yarn guide carried by the nut gear, a ratchet wheel, gearing between the ratchet wheel and the nut gear, a pawl pivotally connected to the support for actuating the ratchet

65

wheel during the movement of the support in one direction, and an adjustable stop screw carried by the support and adapted to be engaged by the pawl to cause the disengagement of the pawl from the ratchet wheel during the movement of the support in the said direction, whereby the extent of movement of the ratchet wheel by the pawl at each stroke of the support may be varied by

70

adjusting said screw.

10. In a yarn winding machine, the combination of a frame, a bobbin spindle, means to rotate the spindle, a vertically movable support guided by the frame, means to reciprocate the support, a non-rotating, verti-

80

cal builder screw carried by the support, a nut gear operatively engaged with the screw, a yarn guide carried by the nut gear, a ratchet wheel, a vertical shaft geared to the ratchet wheel and having an elongated, non- reciprocating pinion geared to the nut gear, and a pawl carried by the support for actuating the ratchet wheel.

85

In testimony whereof I affix my signature

90

hereto.

JACOB K. ALTEMUS.
